UNITED STATES PATENT OFFICE.

CHARLES M. THACKSTON, OF MONTCLAIR, NEW JERSEY.

FERRYBOAT GATE.

Application filed November 11, 1922. Serial No. 600,373.

To all whom it may concern:

Be it known that I, CHARLES M. THACKSTON, a citizen of the United States, and resident of Montclair, in the county of Essex and State of New Jersey, have invented certain new and useful Improvements in Ferry-boat Gates, of which the following is a specification.

One of the main objects of this invention 10 is the provision of a gate for closing a ferry boat exit which will possess sufficient strength to withstand the impact of an automobile or truck and prevent it from running overboard in case the driver should fail to 15 cut off the power or lose control of the vehicle.

Further objects are the provision of a gate of this character which can be easily operated; and the provision of a gate structure 20 so designed that it may be mounted upon a ferry boat with but very little alteration in the boat structure.

In the drawings:

Fig. 1 is a top plan view of an end of a 25 ferry boat showing the gate structure mounted thereon;

Fig. 2 a vertical section taken on the line 2—2 of Fig. 1 looking toward the inner side of the gate;

Fig. 3 a horizontal section taken through 30 one of the gate housings on the line 3—3 of Fig. 5, one of the gate sections being shown in top plan;

Fig. 4 a detail vertical section taken on the 35 line 4—4 of Fig. 1;

Fig. 5 a view of the inner side of one of the gate housings and of portions of the gate sections, parts being in section in order to show the gate locking means;

Fig. 6 a vertical section taken on the line 40 6—6 of Fig. 4;

Fig. 7 a horizontal section through the meeting ends of the two gate sections taken on the line 7—7 of Fig. 5;

Fig. 8 an end view of one of the gate sections;

Fig. 9 a vertical section taken on the line 45 9—9 of Fig. 5; and

Fig. 10 a vertical sectional view through 50 the meeting ends of the gate sections showing the locking means released.

Referring to the parts by numerals, 1 designates the deck of a ferry boat and 2 the hull. The deck 1 overhangs the hull as 55 at 3, this structure being common in ferry boats. A pair of gate housings 4 are mount-

ed upon the deck at opposite sides of the boat, near its end and adjacent the side edges of the deck. The outer ends 6 of the housings 4 are spaced apart sufficiently to 60 provide an exit therebetween. The housings 4 take the place of the usual bulwarks and are preferably made of metal. The form of the housings is yoke-shape in cross section, as shown in Fig. 6, each of said housings comprising a top 7, spaced, downwardly diverging, inner and outer sides 8 and 9 respectively formed integral with the top, and outturned flanges 10 formed at the lower edges of the sides. The flanges 10 are bolted 70 to the deck as at 11 to hold the housing securely in place. The housings 4 take the place of the usual bulwarks near the end of a ferry boat and are curved in a manner substantially similar to said bulwarks. The 75 curvature of the housing adapts it to receive and guide one of a pair of gate sections 12 and 13. A pair of arcuate tracks 14 are secured to the deck 1 and are countersunk therein. The tracks 14 extend from 80 points near the inner ends of the housings, through the said housings midway between the sides 8 and 9 and outwardly to the center of the exit where the said tracks meet near the end of the deck.

Each of the gate sections 12 and 13 is preferably formed of metal and comprises a pair of spaced inner and outer arcuate plates or sheets 15 and 16 respectively. The plates 15 and 16 are held spaced apart at their 85 upper edges by an arcuate channel-iron 17 and spaced apart intermediate their upper and lower edges by a pair of spaced, arcuate I-beams 18. The vertical edges of the plates 15 and 16 at the outer ends of the gate 90 sections are bound by the channel-irons 19. The gate sections conform in curvature to the curvature of the tracks and the housings and the said gate sections are provided with wheels or rollers 20 which run upon the 95 tracks. The rollers 20 are mounted in yokes 21 which are secured to the gate sections between the plates 15 and 16 and the said rollers have flanges 22 which run in grooves 23 formed in the tracks 14. In order to 100 assist the tracks 14 in guiding the movements of the gate sections and to hold the sections upright, the housings have rollers 24 mounted as at 25 upon the opposed inner walls of the housings and spaced along the length of 110 the housings, the rollers upon the opposed walls being directly opposite each other.

The rollers 24 contact the opposite sides of the gate sections and serve to guide and support the gate sections. An additional supporting and guide roller 26 is mounted upon the top of each gate section near the inner end of said section as at 27. The roller 26 rotates upon a vertical pivot and runs between a pair of guides 28, which are mounted upon the under side of the top 7 of the housing 4. The guides 28 extend throughout practically the entire length of the housing.

A shaft 29 extends transversely through the end of the hull of the ferry boat and is adapted to be rotated by a motor 30 secured to the under side of the deck. The shaft 29 rotates in sleeves 31 mounted in the sides of the hull, and the ends of the shaft, which extend beyond the outer sides of the hull, have bevel gears 32 keyed thereto. The gears 32 engage gears 33 which are fixed to the lower ends of a pair of vertical shafts 34, the said gears being protected by a suitable housing 35. The shafts 34 extend upwardly through the deck and into the housings 4, near the outer or forward ends of the said housings, and the said shafts have gears 36 keyed thereto at their upper ends. The gears project outwardly through slots in the inner sides of the housings and are protected by guards 37. An arcuate rack 38 is mounted upon the inner face of the outer side plate 16 of each gate section. The rack 38 extends for most of the length of the gate section and is located between the I-beams 18. The inner side plate 15 of each gate section is slotted directly opposite the rack 38, as at 39, in order to permit the cooperating gear 36 to project through and engage the rack.

From the foregoing it will be seen that when the motor 30, which may be controlled from any suitable point on the boat, is operated to rotate the shaft 29 in one direction the gate sections will be moved in unison through the gearing, just described, to their open position within the housings 4. When the motor rotates the shaft 29 in the reverse direction the gate sections will be moved in unison outwardly from the housing and forwardly until their outer ends meet at the center of the exit.

In order to prevent shocks in the opening and closing of the gate sections, suitable cushioning means are provided. The means for cushioning the closing of the gate comprise a plurality of compression springs 40 mounted upon abutments 41 fixed to the housings 4 near the outer ends thereof and upon opposite sides of the gate sections. When the outer ends of the gate sections approach near to each other in their closing movement, the springs 40 are compressed between the abutments 41 and abutments 42 carried by the inner ends of the gate sections thus causing a resistance

which slows up the final closing movement of the gate sections.

The means for cushioning the opening of the gate comprises a plurality of compression springs 43 mounted upon plates 44, secured to the inner ends of the housings 4. When the inner ends of the gate sections approach the limit of their opening movement the springs 43 will be compressed between the plate 44 on the housing and a plate 45 on the inner end of the gate sections.

When the outer ends of the gate sections meet in the closing operation they are automatically locked together. The means for locking the gate sections together comprise a series of pivoted latches mounted upon each gate section, the latches upon one section being adapted to engage the other section and vice versa. The latches are designated by 46 and are pivotally mounted as 47 upon the ears 48 secured to the inner sides of the end walls formed by the channel-irons 19. The latches 46 extend outwardly through openings 49 in the end wall of the gate section to which they are attached and through an opening 50 in the end wall of the other gate section, the latches being formed with shoulders 51 adapted to lock the two sections together. The latches upon each gate section are connected together rearwardly of their pivots by a vertical rod 52 which is adapted to slide through openings 53 in the beams 18. The rods 52 compel the latches to move in unison and the said latches are held in operative position by springs 54 connected to the upper ends of the rods 52 and to the tops of the gate sections. The latches may be moved to unlocking position by pressing downwardly upon a stirrup 55 pivotally connected to the lower end of one of the rods 52. The stirrup 55 projects through an opening 56 in the lower edge of the plate 15, and a shoulder 57 is formed at one side of the opening. When it is desired to retain the latches in release position the stirrup 55 is depressed and swung to one side to engage the shoulder 57. Only one of the gate sections is provided with a stirrup 55, the latches on the other section being released indirectly by means of a small vertically slidable rod 58 resting at its lower end on one of the stirrup operated latches and adapted to be moved upwardly thereby to engage the inwardly projecting end of one of the latches of the other gate section and rock it and its companion latches to release position. The outer ends of the latches 46 are beveled to form the cam edges 59. As the gate sections come together the cam edges 59 ride up upon the lower edges of the openings 50 in the other gate sections and rock the latches against the tension of the springs 54 to permit the locking ends of the latches to pass through the 130

openings 50, after which the springs restore the latches to locking position.

It will be obvious that a barrier constructed as the one shown and described will be capable of resisting a powerful outwardly directed force and thus capable of holding automobiles and trucks and preventing them from running overboard as frequently happens in case of loss of control or failure to cut off the power. The strength of the barrier resides in the strength of the gate sections and the locking means and the strength of the housings and of the connections between the housings and the inner ends of the gate sections. To add to the strength of the connections between the housings and the gate sections, an additional pair of rollers 24' is provided near the outer ends of the housings below the rollers 24. When the gate sections close together they are automatically locked rigidly together to form a rigid outwardly bowed barrier strongly connected at its ends to the housings 4.

I do not wish to be limited to the precise structure shown as it is possible to make many changes in the structure of the gate, and of the operating means without departing from the spirit of the invention.

I claim:

1. A barrier for closing the exit of a ferry boat comprising a pair of gate sections adapted to be moved longitudinally on arcuate paths to open or closed position, the said gate sections meeting at the center of the exit in closed position, power-driven means for moving the gate sections to open or closed position, means for automatically locking the gate sections in closed position, means for cushioning the closing of the gate sections, and means for cushioning the opening of the gate sections.

2. A barrier for closing the exit of a ferry boat comprising a pair of rigid gate sections adapted when in open position to be disposed at opposite sides of the exit and movable endwise forwardly and toward each other on arcuate paths to closed position with their outer ends together, means for automatically locking the said outer ends of the gate sections rigidly together to form of said gate sections a rigid outwardly bowed barrier, a pair of arcuate housings fixed to the ferry boat adapted to receive the gate sections when the sections are in open position and adapted to support the said sections and to guide them in their movement, connections between the said housings and the inner ends of the gate sections adapted to resist a force tending to move the barrier outwardly, power-driven means for opening and closing the gate sections, means within the housings for cushioning the opening of the gate sec-

tions and means within the housings for cushioning the closing of the gate sections.

3. A barrier for closing the exit of a ferry boat comprising a rigid arcuate gate adapted to be moved end-wise on an arcuate path to closed position, a hollow arcuate sheet metal bulwark fixed to the ferry boat at one side of the exit and adapted to receive the gate when the gate is in its open position, power-driven means for opening and closing the gate, anti-friction means within the bulwark for supporting the gate and guiding its movement, means within the bulwark for cushioning the closing of the gate, and means within the bulwark for cushioning the opening of the gate.

4. A barrier for closing the exit of a ferry boat comprising a gate adapted to be moved longitudinally to open or closed position, a hollow bulwark fixed to the ferry boat at one side of the exit and adapted to receive and enclose the gate when the said gate is in its open position, power driven means for opening and closing the gate the said means being operatively connected to the gate within the bulwark, and anti-friction means within the bulwark for supporting the gate and guiding it in its movement.

5. A barrier for closing the exit of a ferry boat comprising a pair of rigid arcuate gate sections adapted to be moved on arcuate paths to open or closed position, the said gate sections meeting at the center of the exit in closed position, means at the meeting ends of the gate sections to lock them together and form of said sections a rigid outwardly bowed barrier, means connected to the inner ends of the barrier for resisting a force tending to move the barrier outwardly, and power driven means for moving the gate sections to open and closed position.

6. A barrier for closing the exit of a ferry boat comprising a pair of rigid arcuate gate sections adapted when in open position to be disposed at opposite sides of the exit and movable endwise forwardly and toward each other on arcuate paths to closed position with their outer ends together, means for automatically locking the said outer ends of the gate sections rigidly together to form of the gate sections a rigid outwardly bowed barrier, the said locking means comprising a series of vertically spaced latches carried upon one of the gate sections and adapted to lockingly engage the other gate section when the ends of the said gate sections meet, means for releasing the said latches in unison, and means connected to the inner ends of the barrier for resisting a force tending to move the barrier outwardly.

7. A barrier for closing the exit of a ferry boat comprising a pair of rigid arcu-

ate gate sections adapted to be moved to open and closed positions on arcuate paths, a pair of arcuate sheet metal housings fixed to the ferry boat and adapted to receive 5 the gate sections when the said sections are in their open positions, the said gate sections being hollow and formed with spaced arcuate sheet metal sides, an arcuate rack mounted upon one of the sheet metal sides 10 within each of said gate sections, the opposite sheet metal side of each gate section having a slot therein opposite the said rack, a power shaft extending transversely of the boat beneath the deck, a pair of shafts 15 adapted to be rotated by said power shaft

and extending upwardly therefrom into the gate housings, gears fixed to the upwardly extending shafts, the said gears projecting through the slots in the sheet metal sides of the gate and engaging the racks, whereby the gate sections may be moved to open and closed position in unison upon rotation of the power shaft, and anti-friction means interposed between the inner sides of the 20 housings and the gate sections for supporting and guiding the gate sections. 25

In testimony whereof I hereunto affix my signature.

CHARLES M. THACKSTON.
